US00D946801S

(12) **United States Design Patent** (10) **Patent No.:** **US D946,801 S**
Shen (45) **Date of Patent:** **** Mar. 22, 2022**

(54) **UNDER-BED SENSOR LIGHT OF MEDICAL BED**

(71) Applicant: **TIMOTION TECHNOLOGY CO., LTD.**, New Taipei (TW)

(72) Inventor: **Bo-Yen Shen**, New Taipei (TW)

(73) Assignee: **TIMOTION TECHNOLOGY CO., LTD.**, New Taipei (TW)

(**) Term: **15 Years**

(21) Appl. No.: **29/699,271**

(22) Filed: **Jul. 24, 2019**

(51) LOC (13) Cl. **26-05**

(52) U.S. Cl.

USPC **D26/51**

(58) **Field of Classification Search**

(57) **CLAIM**

The ornamental design for a under-bed sensor light of medical bed, as shown and described.

DESCRIPTION

FIG. 1 is a perspective view of an under-bed sensor light of medical bed showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a second perspective view showing the under-bed sensor light of medical bed.

The broken lines in the drawings illustrate portions of the under-bed sensor light of medical bed that form no part of the claimed design.

1 Claim, 8 Drawing Sheets
